UNITED STATES PATENT OFFICE

2,638,687

APPARATUS FOR COOLING AND DEHYDRATING HOT PULPY SOLIDS

Daniel B. Vincent, Tampa, Fla., assignor to Dan B. Vincent, Inc., Tampa, Fla., a corporation of Florida

Original application November 27, 1945, Serial No. 631,072. Divided and this application March 29, 1949, Serial No. 84,184

4 Claims. (Cl. 34—136)

1

This invention relates to apparatus for cooling and dehydrating hot pulpy solids such as partially dehydrated citrus waste and the like, and aims generally to improve existing apparatus for the purpose.

Citrus cannery waste, i. e. the peel, rags and seed from citrus canneries, is a desirable material for the manufacture of stock and dairy cattle feed. The citrus waste normally contains about 80 to 85 percent or more water and it must be comminuted and substantially dewatered for use. It is customary to dehydrate the comminuted waste by drying to a moisture content of not more than 10 percent to prevent decomposition of the feed. The drying and dehydrating step is usually effected in steam heated or other indirect heat driers and is the most costly step in the manufacture of citrus pulp feed.

Furthermore, the several treatment steps in processes for the manufacture of citrus pulp feed are advantageously arranged in continuous sequence so that the material moves continuously from its untreated state to its final dehydrated state ready to be sacked into sacks or bags. Prior to my invention, the drying or dehydrating step was the final processing step and the finished material emerging from the driers was of approximately 140° F. and too hot to be immediately bagged and sacked. When allowed to cool before sacking, additional handling expense was often involved.

The present application is a division of my prior copending application Serial No. 631,072, now Patent 2,471,363, filed November 27, 1945, disclosing and claiming an improved method and apparatus of producing a desirable feed from citrus cannery waste involving a number of correlated steps comprising (1) a preliminary treatment of the cannery waste with lime or other alkaline compound; (2) comminuting the waste; (3) mixing and reacting the comminuted waste and lime; (4) mechanically pressing the waste to partially remove water; (5) drying the pressed solids in a current of hot products of combustion; and (6) cooling and further dehydrating the hot solids.

The present invention relates to an improved apparatus for cooling and finally dehydrating the hot pulpy solids. The hot solids leaving the primary dehydrating driers of the above described system will usually be at a temperature of about 130° to 140° F. and will contain about 12 or 13 percent moisture. They must then be cooled and further dehydrated to a moisture content of about 10 percent preparatory to packaging for ship-

ment. The cooling and dehydrating apparatus according to the present invention is designed to perform the latter step in an efficient and expeditious manner and to constitute the final treatment step in the continuous processing of citrus cannery waste to produce a citrus feed product ready for packaging or bagging.

A primary object of the invention, therefore, is the provision of an improved apparatus for cooling and dehydrating citrus waste and the like.

Another object of the invention is the provision of an improved apparatus for cooling and dehydrating citrus waste and the like in which a voluminous current of atmospheric air is utilized as the cooling and dehydrating medium.

Still another object of the invention is the provision of apparatus through which partially dehydrated hot citrus pulp material or the like is progressively treated and maintained in spread-out condition in the presence of a voluminous current of room-temperature air preferably under subatmospheric pressure.

A further object of the invention is the provision of apparatus in which partially dehydrated citrus pulp material or the like is subjected to a gentle slipping and sliding movement in spread-out sheets intermittently interrupted by a gentle tumbling or turning action in the presence of a current of air at subatmospheric pressure.

These and other objects and advantages of the invention will be apparent to persons skilled in the art from a consideration of the attached drawings and annexed specification illustrating and describing preferred embodiments of the invention.

35 In the drawings—

Fig. 1 is a side elevational view partly in section of one form of cooling and dehydrating drum embodying the invention and suitable for practicing the method hereinafter described and claimed;

Fig. 2 is an enlarged fragmental sectional view of the inlet end of the drum;

Fig. 3 is an enlarged fragmental sectional view of an intermediate section of the drum;

Fig. 4 is an enlarged transverse sectional view of the drum as taken on the line 4—4 of Fig. 1, and illustrating the cascading movement of the material from a shelf on the ascending side thereof; and

Fig. 5 is a view similar to Fig. 4 illustrating the cascading movement of the material from a shelf on the descending side of the drum.

In general, the invention comprises moving the hot moist pulpy solids in a confined annular path,

as between concentric shells of a rotary drum, the solids being spread out in sheet form on supporting shelves for a major portion of the time, the material being successively and repeatedly transferred from one supporting surface to another by a gentle cascading action involving only a very short fall so that a minimum of fines may be carried off in the current of air. In cascading the material from one supporting surface to another the fall is substantially less than the length of a chord of the drum passed through a free edge of a supporting shelf, and preferably the cascading drop is less than half the length of such a chord. In this way the solids are only very briefly in suspension which permits the use of a much larger volume of air with correspondingly increased evaporating effect, and hence a more rapid and efficient cooling and dehydration.

According to a preferred embodiment of the invention, the hot, moist pulpy solids, for example the partially dehydrated citrus pulp delivered from the separating device of a primary dehydrating drier (not shown) is delivered to a cooling and dehydrating drum 10 by means of a feed chute 11, the drum 10 providing a confined path for supporting and traversing the material to be cooled and dehydrated in substantially spread-out condition through a large volume counter-current of cooling air.

The drum 10 preferably comprises an outer shell 12 and a concentric inner shell 13 suitably connected together for rotation in unison as a unitary structure and providing therebetween an annular passage through which the material to be treated is moved in a spiral or helical path. The inlet end of the drum 10 may be provided with a frusto-conical casing 15 surrounding the feed chute 11 and having its large end fitted to an inwardly extending flange 14 on the inlet end of the drum to permit relative rotation therebetween. The casing 15 provides a suction chamber surrounding the inlet chute 11 and is connected at its smaller end to the intake part of a motor driven fan 17 having its discharge outlet 18 leading to a centrifugal separator 19 of suitable design.

The concentric drum shells 12 and 13 are suitably connected in spaced-apart relation by any suitable means, as for example by spokes (not shown), so that they may be rotated in unison. Any suitable means may be provided for rotating the drum 10, and in the illustrated embodiment the outer shell 12 may be provided with circumferential bands or tires 20 supported on and driven by rotating rollers 21 as is well understood in the art. Generally, the drum will be rotated at from about 5 to 15 R. P. M. and preferably at about 10 R. P. M. for best results.

The concentric shells 12 and 13 are provided with material-supporting plates or shelves 22 and 23 respectively, arranged in staggered relation within the annular chamber between the shells and are designed, in conjunction with the shell surfaces, to support the material to be treated in spread-out condition for a major portion of the time it is within the drum. The shelves 22 and 23 are advantageously sheet metal plates disposed radially of the shell surfaces and longitudinally thereof and are of substantial width, preferably exceeding one-half the width of the annular chamber between the concentric shell surfaces. Preferably the shelves 23 on the inner shell 13 are disposed intermediate the shelves 22 on the outer shell 12, as shown, and their adjacent surfaces overlap. Obviously the number of

shelves on the respective drums may be varied in accordance with the requirements of the material to be cooled and dehydrated, but for practical purposes a minimum of four shelves on each of the shells is desirable.

The plates or shelves 22 and 23 preferably stop somewhat short of the inlet end of the drum to form an inlet section 24 for receiving the material from the feed chute 11. To assist in moving the material from the inlet section 24 into engagement with the plates 22 and 23 one or more spirally arranged blades 25 are secured to the inner periphery of the outer shell 12 and are preferably positioned so that they form continuations of the outer plates 20. These act to move the material quickly through the inlet section 24 to be engaged and lifted by the plates 22 and 23.

As will be apparent from Fig. 1, the drum 10 is inclined downwardly slightly from the inlet or feed end to the discharge end so that rotation thereof will progress the material through the annular passage therebetween at a speed designed to accomplish the desired cooling and dehydrating effects. Generally the angle of inclination of the drum with respect to the horizontal will vary from about 3 to about 8 degrees depending upon other factors including the characteristics of the material being treated, the size and construction of the drum and the revolutions per minute. If desired, the spiral blade 25 may be continued along the inner surface of the outer shell 12 throughout the length thereof to facilitate movement of the material longitudinally through the drum.

In operation the hot pulpy solids and like material entering the revolving drum through the feed chute 11 falls into the inlet section 24 where it slides downwardly under the action of gravity and the conveying action of the spiral blades 25 until it is engaged by one of the plates 22. This plate acts as a shelf to lift the material as the drum rotates, and as the shelf approaches a vertical position, the material slides off and is cascaded into the space between two plates 23 upon the convexed surface of the inner shell 13. With continued rotation the material may be carried over to the other side of the drum where it slides off of a plate 23 and drops onto the concaved surface of the outer drum. When the next plate 22 reaches the fallen mass the operation is repeated.

Due to the inclination of the drum and of the shelves 22 and 23 carried thereby the material is shifted along the shelves and advanced along the drum as compared to that which it occupied at the bottom of the drum. Likewise as the material cascades from the plates 22 to the convexed surface of the inner shell 23 and from there to the bottom of the outer drum it strikes advanced portions of these surfaces and is further advanced along the drum toward the discharge end thereof. During this progressive movement of the material through the drum a current of air is drawn therethrough by the blower 17 over the material as it lies spread out and as it cascades from one shelf to another. In addition, air is drawn also along the supporting shelves and through the inner shell 13 thereby cooling them so that it exerts a cooling effect on any material resting thereon and on the air passing between the shells. Practically the entire movement of the material through the drum is that of slipping and sliding along in spread-out sheets which are separated and re-formed at each tumbling or cascading drop from one plate to an adjacent

surface. This cascading or drop is of such short length, preferably less than half the length of a chord of the drum 10 passed through a free edge of the shelves 22 or 23, that a large volume of cooling air may be employed without danger of carrying off an excessive amount of fines or similar particles. This enables the current of air at subatmospheric pressure to carry off any escaping moisture from the hot material to continue the drying operation by evaporation of water and to cool the material quickly by the refrigerating effect of the evaporation.

Normal atmospheric air can be used as the drying medium even on very humid days because the entering air encounters material of a warmer than atmospheric temperature and it becomes progressively warmer as it encounters still warmer material. The capacity of air for carrying moisture is approximately doubled with every 20° F. rise in temperature. Assuming an outside temperature of 72° F., feed entering the cooling drum at 140° F. and the air entering at 72° F. and leaving at 132° F., it will be seen that the rise of 60° F. in the temperature of the air has almost doubled its water-carrying capacity three times, giving a final capacity of about six times the original capacity. Competent authorities state that one pound of air at 72° F. will carry 0.016691 pound of water while one pound of air at 132° F. will carry 0.118548 pound of water. Hence, under the conditions stated, each pound of air circulated through the drums has the potentiality of picking up about 0.10157 pound of water.

As the cooled and dehydrated material passes from the open discharge end of the drum 10 it falls into a discharge chute 30 from which it may be conveyed to a suitable sacking or packaging device, not shown. The material passed through the drum will have been cooled from approximately 140° F. to approximately 75° F. and will have been dehydrated from a moisture content of about 12 or 13 percent to about 10 percent or less.

Thus the present invention provides an apparatus which is highly effective for its intended purpose of cooling and dehydrating hot waste material such as treated citrus waste. It has the advantage that solids passing between the drums are continuously subjected to a slipping, sliding and tumbling action so that the individual particles thereof are uniformly and completely exposed to the cooling and dehydrating effects of the current of subatmospheric air. It has the further advantage that atmospheric air may be used without prior conditioning, thus eliminating the need of costly and complicated apparatus for this purpose. Although designed primarily for cooling and dehydrating treated citrus waste, the apparatus of this invention is applicable to the treatment of other materials of a similar nature and such uses are contemplated as within the scope of the invention.

Various modifications of the invention described and illustrated will most likely occur to those skilled in the art to which the invention relates and may be made without departing from the spirit of the invention, the scope of which is indicated in the attached claims.

I claim:

1. An apparatus for cooling and dehydrating hot solids comprising a rotatably mounted drum member having inner and outer cylindrical shells, said inner shell having a substantial surface area concentric with the outer shell whereby there

is defined an annular space therebetween, inlet means for feeding hot solids into one end of said drum member, outlet means for discharging cooler treated solids from the opposite end of said drum member, a plurality of shelf plates secured to the inner surface of said outer shell longitudinally thereof and extending inwardly toward said inner shell and terminating in inner edges spaced from said inner shell, a plurality of shelf plates secured to the outer surface of said inner shell longitudinally thereof and extending outwardly between said first named plate members in overlapping relation therewith and terminating in outer edges spaced from said outer shell, a spiral feed band extending inwardly from the inner surface of the outer shell into proximity with the outer edges of the shelf plates on the inner shell, the last said shelf plates being attached to the inner margin of the spiral feed band, said drum member being inclined downwardly from the inlet to the outlet ends whereby material introduced into said outer drum will be progressed therethrough with a cascading, sliding and slipping movement over the surfaces of the inner and outer shells and the shelf plates, and means for subjecting the material to a current of air as it moves through said outer drum member to cool and dehydrate it.

2. An apparatus for cooling and dehydrating hot solids comprising a drum member, inlet means for introducing hot solids into said drum member for passage therethrough, a spirally arranged band secured to the inner surface of said drum member and extending throughout a substantial portion of its length, a plurality of longitudinally extending plates mounted in said drum member and having portions thereof positioned between the turns of said spiral band and secured to the inner surface of said drum member, an inner shell mounted in said drum and held in position therein by a plurality of longitudinally extending plate members, said plate members having their inner edges secured to said inner shell and their outer edges secured to the turns of said spiral band where they come into contact, means for rotating said drum member and said inner shell, and means for passing a current of air through said drum member in contact with the hot solids passing therethrough.

3. An apparatus for cooling and dehydrating hot solids comprising a drum member, means for introducing hot solids into said drum member for passage therethrough, a spirally arranged band secured to the inner surface of said drum member and extending throughout a substantial portion of its length, a plurality of longitudinally extending plates mounted in said drum member between the turns of said spiral band and extending radially inward therefrom, an inner shell mounted in said drum member concentrically thereof, plate members secured to said inner shell and extending outwardly intermediate said first mentioned plate members, the last said plate members being secured at their outer portions to the inner margin of the spiral band, means for rotating said drum member and said inner shell, and means for passing a current of air through said drum member in contact with hot solids passing therethrough.

4. Apparatus for continuously cooling moist hot pulpy solids of a moisture content of at least 12 percent and dehydrating them to a moisture content of not more than 10 percent comprising a rotary drum having concentric inner and outer shells presenting radially opposed concaved and

convexed surfaces, inlet means for introducing hot pulpy solids to the space between said shells at one end of said drum, means for discharging treated material from the opposite end of said drum, means for establishing a large volume current of cooling air through said drum between said shells in a direction counter to the movement of solids therethrough, a plurality of shelf plates secured to the inner surface of said outer shell longitudinally thereof extending inwardly therefrom and terminating in edges spaced from said inner shell for lifting material from the bottom of the outer of said shells, carrying it upwardly in spread-out form thereon, and cascading it downwardly onto the upper convex surface of the inner of said shells, a plurality of shelf plates secured to the outer surface of said inner shell longitudinally thereof extending outwardly therefrom and terminating in edges spaced from said outer shell for carrying material cascaded downwardly on said upper convex surface upwardly and over to the opposite side of the drum while spread out thereon, and then cascading it downwardly to the concave surface of said outer shell, the outer edges of the shelf plates on the inner shell overlapping the inner edges of the shelf plates on the outer shell, and a spiral feed band extending inwardly from the inner surface of the outer shell, the outer portions of the shelf plates on the inner shell being secured to the

margin of the spiral band, whereby the inner shell is secured to the outer shell and the spiral band feeds the solids longitudinally of the drum when the solids are on the inner periphery of the outer shell.

5 DANIEL B. VINCENT.
